(57) **CLAIM**

We claim the ornamental design for a remote control, as shown and described.

DESCRIPTION

FIG. 1 is a front elevation view of a remote control of the present invention.

FIG. 2 is a rear elevation view of the remote control shown in FIG. 1.

FIG. 3 is a side elevation view of the remote control as viewed from the left side of FIG. 1.

FIG. 4 is a side elevation view of the remote control as viewed from the right side of FIG. 1.

FIG. 5 is a top plan view of the remote control shown in the prior Figures.

FIG. 6 is a bottom plan view of the remote control shown in prior Figures; and,

FIG. 7 is perspective view of the top, front and right sides of the remote control shown in the prior Figures.
